RUNNER FOR TURBINES

Original application filed April 15, 1922, Serial No. 553,294. Divided and this application filed June 14, 1926. Serial No. 115,751.

This invention relates to hydraulic turbines and to the formation of the rotary element or runner of turbines or pumps and particularly to runners of the unshrouded 5 blade type. In prior practice it has been usual to form the runners of turbines or pumps with the blades or vanes in one integral casting or inseparably connected to the hub so that it is necessary to provide for removal of the whole runner as a unit for repair 10 or replacement. In many installations this greatly increases the cost of the turbine or pump, and it is highly desirable to be able to remove the runner vanes separately and then, if necessary, to remove the hub. If a vane is 15 injured by striking an obstacle, if corrosion occurs, if the vane shape is to be changed by chipping to alter or correct the operating characteristics, in any of these contingencies 20 it is the vanes which require removal and not the whole runner.

One object of the invention is to provide a runner in which the blade sections are adjustable so as to vary the blade angles with 25 relation to the flow and permit the operating characteristics to be changed.

In the accompanying drawings illustrating the invention—

Fig. 1 is a vertical sectional view of a turbine structure showing a runner formed in accordance with this invention.

Fig. 2 is an enlarged sectional view of a blade of the runner of Fig. 1.

Figs. 3 and 4 are a plan and sectional elevation of a runner illustrating a modification.

Figs. 5, 6 and 7 are sectional views illustrating a further modified form.

Figs. 8, 9 and 10 are sectional views illustrating another form of runner, and

Figs. 11 and 12 are elevational and sectional views, respectively, of a further modification.

In the embodiment of the invention shown in Figs. 1 and 2, the flow entering through the 45 adjustable guide vanes 50 passes downward and inward through the blades 51 of the runner R and out through draft tube d. The blades 51 are detachable and adjustable and are rotatably held in the hub 52 by a journal or pintle 55 engaged by the set screw 56.

The surface 54 of the hub 52 is spherical around a center formed by the intersection of the vertical axis of the runner with the axis of the pintle 55. The inner edges of the 55 blades 51 are shaped to conform to the spherical surface 54 of the hub 52 so as to contact therewith in all adjustments. The front face f of each blade 51 is approximately flat as shown in Fig. 2 while the back surface b is arched to give a sufficient thickness to the 60 blade at its junction with the pintle to avoid breakage at this point. Under the pressure of the flow against the front surface f of the 65 blade, the front elements at the area of attachment to the pintle 55 are under tension at t while the rear elements are under compression at c.

In the modified form shown in Figs. 3 and 4 there are four blades 66 extending in a 70 diagonal direction directly across the diagonally inward flow lines. The central hub portion 60 adapted for keying to the shaft is of generally conical form and is provided with four inclined circular recesses 61 in which are rotatably fitted the pintles 62 of 75 the vane sections. Set-bolts 63 are provided having their inner ends engaging in grooves 64 in pintles 62 and their heads countersunk in recesses 65 at the top of the hub 60. The 80 ends 67 and 68 of the vanes 66 are formed so as to permit a slight angular rotation of the vane to either side of a designed central position, the vane and pintle turning as a whole around the axis of the pintle 62. These pintles have their axes inclined at an angle to a 85 plane perpendicular to the axis of the runner and the pintle axes are substantially perpendicular to the elements of the conical surface of the hub intersected by them. In order to adjust these vanes it is only necessary to loosen the set-bolts 63, turn the vanes, and then reset the set-bolts to hold the vanes in adjusted position.

In Figs. 5 to 7 the runner hub 70 of conical form has four tapered circular recesses 95 71 in which are fitted tapered circular disks 72 carrying vanes 73 which are thus rotatable about an inclined axis 74. To hold the vanes in adjusted position bolts 75 are provided passing through slots 76 of the disks 72 and 100

serving when tightened to clamp said disks tightly in said recesses.

In the modified form of runner shown in Figs. 8 to 10, the hub 78 is provided with three circular recesses 79 in which are fitted annular clamping rings 80 within which in turn are rotatably fitted disks 81 of vanes 82. Each clamping ring 80 is in separate halves. Each disk 81 has an enlarged head portion 83 engaged by the inner edge of the clamping ring 80 and bolts 84 are provided to press the clamping ring against said head 83 to grip the latter against the bottom of the recess 79 and thus securely hold the runner section against rotation from its adjusted position. The enlarged pintles provided by the disks 83, 81 not only give the extending surface for the fitting of the rotatable parts but also provide a large area at the surface of connection of the disk with the blade so as to attain a strong construction.

In the runner shown in Figs. 11 and 12, a shaft 85 carries a central hub portion 86 of generally conical form keyed to the tapering end of the shaft. The hub portion 86 has a series of four circular recesses 87 in which are rotatably fitted the disks 88 of the blade sections having vanes 89. A lower holding ring 90 is fitted to the lower half of the hub portion 86 and has its upper edge horizontal and cut out in semi-circular form fitted to the periphery of the secondary disks 91 of the blade sections and overhanging the lower halves of the main disks 88. Fitted to the upper half of the hub section 86 are a series of segmental plates 92 each of which has its lower edge cut out in a semi-circle meeting with the corresponding semi-circle of the lower ring 90 and fitting the remaining half of the secondary disk 91. A cap member 93 having a depending flange 94 fits over the top of the hub portion 86 and retains the plates 92 by their engagement under the flange 94. Locking bolts 95 are provided passing through slots in disks 91, 88 and serving to clamp the disk and blade section securely in adjusted position.

In all of the modified forms the exposed surfaces of the vane sections are rounded off to correspond to the conical formation of the hub and to give smooth unobstructive flow lines. The feature of adjustability permits the runner characteristics to be altered to conform to particular conditions of individual installations. In case of change of head or quantity of water available the blades may be shifted to take advantage of the change and at the same time maintain the efficiency of the turbine. The adjustability of the runner vanes may also be used to test out the performance of the turbine for various inclinations of the blades and for various settings of the turbine gates.

The adjustable bladed runners of this invention are adapted for a new method of

testing turbines and a new method of developing improved turbine designs. The large number of variables entering into hydraulic turbine design and the large part played by hydraulic surface friction, particularly in the performance of turbines of the high speed type here involved, introduce uncertainties and make it difficult to determine the best design of turbine. The method of this invention consists in equipping a small test turbine with runner blades of a given design and then making a complete test of the turbine with the blades in each of a number of different angular positions by rotatably adjusting them in the hub, as above described. It has been found that in the majority of cases a maximum angular adjustment of about twenty degrees is amply sufficient to cover the useful range of performance. The work of experimental development can be conveniently conducted by first placing the blades in one position and determining the performance of the turbine for various angles of the guide vanes from closed to wide-open position. The runner blades are then adjusted by rotating through an interval of five degrees from the first position and the entire test repeated. A similar procedure is followed for each five degree-interval through the range of adjustability. From these tests, complete curves of performance can be drawn showing the range of performance to be secured from the given design of blade. The runner for any required installation can be designed by selecting the most suitable angle of inclination of the runner blades from these data, the runner for the installation being then built either with adjustable or non-adjustable blades, and with either an integral or sectional runner construction, as the conditions may require.

In the forms of runner illustrated herein, the vanes are of the generally diagonal type, extending directly across the diagonally inward and downward flow lines and having their shape conforming to substantially straight line directrices.

This application is a division of the co-pending application of L. F. Moody, Serial No. 553,294, filed April 15, 1922, for Runner for turbines.

I claim:

1. The combination in a hydraulic turbine comprising a flow conduit and a runner disposed therein having a central hub portion of generally conical form, a plurality of separable vane sections detachably fitted in said hub portion and rotatably adjustable with relation thereto around axes perpendicular to the elements of the conical surface of the hub.

2. The combination in a hydraulic turbine comprising a flow conduit and a runner disposed therein having a central hub portion of generally conical form, a plurality of separable vane sections detachably fitted in said

- hub portion and rotatably adjustable with relation thereto around axes perpendicular to the elements of the conical surface of the hub, and means for fastening said vane sections rigidly in adjusted position. 5
3. In a runner for a turbine the combination with a central hub portion having a generally conical form, of a plurality of separable vane sections detachably fitted in said hub portion and rotatably adjustable with relation thereto around axes, perpendicular to the elements of the conical surface of the hub, and means for fastening said vane sections rigidly in adjusted position comprising 10 pivot portions on the vane sections and bolting means adapted to grip said pivot portions in a direction having a component axially of said pivot portions.
4. In a runner for a turbine the combination with a central hub portion of a plurality of separable vane sections detachably fitted in said hub portion and rotatably adjustable, through a small angle with relation to said hub portion, around axes inclined to a flame 15 perpendicular to the axis of the runner, said vane sections being disposed the same radial distance from the runner axis for various adjustments thereof and means for fastening said vane sections rigidly in adjusted position by exerting a clamping force on said vane section in substantially the direction of the axis about which said vane section is adjusted. 20
5. In a runner for a turbine the combination with a central hub portion of a plurality of separable vane sections detachably fitted in said hub portion and rotatably adjustable, through an angle not exceeding twenty degrees with relation to said hub portion, 25 around axes inclined to a flame perpendicular to the axis of the runner, clearance being provided between said vane sections and said hub portion just sufficient to permit said angular motion and at least a portion of said clearance being maintained constant for various 30 adjusted positions of said vane sections, and means for fastening said vane sections rigidly in adjusted position, each of said vane sections including a blade extending substantially in the direction of the axis about which the vane is adjusted. 35
6. The combination in a hydraulic turbine comprising a flow passage, a runner disposed therein having a central hub portion, a series 40 of independently rotatable vane sections detachably fitted in said hub and rotatably adjustable with relation thereto around axes inclined to a plane perpendicular to the axis of the runner, and a series of bolts passing through said sections and threaded into said hub to clamp said sections in adjusted position. 45
7. The combination in a hydraulic turbine runner comprising a central hub portion, a series 50 of independently rotatable vane sections detachably fitted in said hub and rotatably adjustable with relation thereto around axes inclined to a plane perpendicular to the axis of the runner, and a series of bolts passing through said sections and threaded into said hub to clamp said sections in adjusted position. 55
- tions detachably fitted in said hub and rotatably adjustable with relation thereto around axes inclined to a plane perpendicular to the axis of the runner, and a series of bolts passing through said sections and threaded into said hub to clamp said sections in adjusted position, said sections being provided with elongated openings for said bolts. 60
8. The combination in a hydraulic turbine runner comprising a central hub portion of generally conical form and provided with recesses, of a series of adjustable vane sections fitted in said recesses and rotatably adjustable with relation thereto around axes perpendicular to the elements of the conical surface of the hub, each vane section carrying a disk having smooth peripheral supporting surfaces for contact with the walls of its co-operating recess, and clamping bolts extending through said disk into said hub to clamp said sections in adjustable position. 65
9. The combination in a hydraulic turbine runner comprising a central hub portion of generally conical form, a series of adjustable vane sections fitted in said hub portion and rotatably adjustable with relation thereto around axes perpendicular to the elements of the conical surface of the hub, each vane section carrying a disk provided with elongated openings therein and clamping bolts extending through said openings and threaded into said hub to clamp said sections in adjustable position. 70
10. The combination in a high specific speed substantially axial flow propeller type hydraulic turbine comprising a flow passage, a runner disposed in said passage and having a hub carrying a substantially small number of unshrouded blades which are relatively flat in the direction of flow thereover, and means for supporting said blades for adjustment around axes inclined to the runner axis, each of said blades extending substantially along their respective axes of adjustment whereby during various positions of blade adjustment the center line of each blade retains substantially the same relative position to each other. 75
11. The combination in a hydraulic turbine comprising a flow passage, a runner having blades disposed in said passage, and means for supporting said blades for adjustment around axes inclined to the runner axis, said inclined axes being substantially in alignment with the longitudinal axes of the blades. 80
12. The combination in a hydraulic turbine comprising a flow passage, a runner having blades disposed in said passage, means for supporting said blades for adjustment around axes inclined to the runner axis, and means for whirling the fluid flowing through said passage. 85
13. The combination in a hydraulic turbine comprising means forming a passage turning from a radial to an axial direction 90

- and bounded by relatively smooth curving walls, vanes disposed in said radial portion for whirling the flow passing into said axial portion, and a runner disposed in said passage provided with blades spaced from said vanes to form a transition space therebetween, said runner having means for adjustably supporting said blades around inclined axes substantially coinciding with the blade axes.
- 10 14. The combination in a hydraulic turbine runner comprising a hub carrying blades, and means whereby said blades are adapted to be rotatably adjusted including a tapered circular recess formed in said hub and a correspondingly tapered circular disc carried by a blade for cooperation with said recess, and means for holding said disc within said recess and permitting rotative adjustment of said blades.
- 15 15. The combination in a hydraulic turbine runner comprising a hub carrying blades, and means whereby said blades are adapted to be rotatably adjusted including a tapered circular recess formed in said hub and a correspondingly tapered circular disc carried by a blade for cooperation with said recess, said disc having a series of elongated openings therein, and a series of bolts extending through said disc and threaded in said hub.
- 20 16. In a hydraulic turbine runner, the combination comprising a hub section carrying a blade section, and means permitting rotatable adjustment of said blade section, including a recess formed in one of said sections with a smooth peripheral wall, the other of said sections having a cooperating disc adapted to be received within said recess, and bolts extending through said blade section for threaded engagement with the hub section.
- 25 17. The combination in a turbine having means forming a flow conduit and provision for imparting a whirling component to the inflowing fluid, and a runner comprising a central hub portion having a relatively smooth and uniform contour constituting a substantially smooth continuation of the wall of said flow conduit, said hub having a series of independently rotatable blade sections adjustably fitted in said hub and rotatably adjustable with relation thereto around axes inclined to a plane normal to the axis of the runner, said blade sections being disposed the same radial distance from said conduit wall for various adjustments of the blade sections, and a circular series of bolts extending through said sections and engaging said hub to clamp said sections in fixed adjusted positions.

LEWIS FERRY MOODY.
